UNITED STATES PATENT OFFICE.

EUGENE D. CHELLIS, OF PORTLAND, MAINE; GERRY L. BROOKS, OF PORTLAND, MAINE,
ADMINISTRATOR OF SAID CHELLIS, DECEASED, ASSIGNOR TO NATIONAL METAL
SEAL CORPORATION, OF BOSTON, MASSACHUSETTS, A CORPORATION OF MAINE.

CRIMPING-TOOL.

1,067,797.

Specification of Letters Patent. Patented July 22, 1913.

Application filed March 23, 1911. Serial No. 616,540.

To all whom it may concern:

Be it known that I, EUGENE D. CHELLIS, a citizen of the United States, residing at Portland, county of Cumberland, State of Maine, have invented certain new and useful Improvements in Crimping-Tools, of which the following is a specification.

This invention relates to crimpers and particularly to crimping tool for turning 10 the engaging fingers of a closure under the shoulder of a vessel mouth.

In many lines of packaging it is extremely desirable that the closure be permanently attached to the mouth of the vessel 15 so that it may not be removed after filling. This is well illustrated in modern packaging of oils, varnishes and similar materials which are put up in metallic cans or in containers having a metallic mouth or 20 nozzle.

The requirements, difficulties and practice in this art may perhaps be best understood by reference to particular types and for the 25 purposes of illustration, my present invention will be discussed in the terms of a specific type of closure and of container mouth.

In the application of my swinging metal seal shown in my previous United States Letters Patent, No. 882,547, 882,549 and 30 882,550, to a metal vessel having a flanged or shouldered rim it has been found desirable to clench the shoulder engaging fingers under the rim after the vessel has been filled and sealed in order to prevent refilling or 35 otherwise tampering with the contents. To this end I have devised my present invention in which I have provided for the turning of these fingers into close contact with the flange of the can, thus locking the closure 40 securely in place.

The construction and operation of my device will be more fully disclosed in the specification which follows and an illustrative embodiment, which I have found satisfactory in the practical working of my invention, is shown in the drawings. I also show 45 illustrations of the closure and vessel mouth to which it is applied.

Throughout the specification and drawings like reference numerals are employed 50 to indicate corresponding parts and in the drawings.

Figure 1 is a side sectional view of my tool, and Fig. 2 is a bottom view of the

same with the follower removed, Fig. 3 55 is a plan view of one of my removable dies. Fig. 4 is a front view of the same, and Fig. 5 is a fragmentary view showing the turning groove of the die. Fig. 6 indicates the construction of a smaller sized die than that 60 shown in Fig. 3. Fig. 7 is an enlarged detail, an end section showing a closure and can lip prior to clenching. Fig. 8 is a similar view after clenching. Fig. 9 is a view 65 of the cap to be applied. Fig. 10 is a view of a can neck upon which the closure of Fig. 9 is to be clenched.

1 is a segmental base having a supporting shoulder 2 mounted in any suitable way as over a notch in a bench or table (not 70 shown). 3 are legs formed on said base supporting the tubular column 4 in which is mounted for vertical reciprocation a plunger 5. The plunger 5 is recessed at its lower end as at 6 and is surrounded near its 75 upper end by a collar 7 secured to it by a pin 8.

9 is a sleeve within the column 4 held by a set screw 10.

11 is a spring coiled about the plunger 5 80 and abutting at its lower end against the sleeve 9 and at its upper end against the collar 7 thus normally tending to hold the plunger up to permit the plunger to be depressed into the position shown in Fig. 1. 85

Above the tubular bore of the column 4 is formed a handle 12 and a coöperating handle 13 is pivoted at 14 between ears formed at the upper end of the column 4.

15 is a link pivoted to the plunger 5 at 16 90 and between ears on the under side of the handle 13 as at 17.

18 is a screw stop with a lock nut 19 threaded into a projection 20 on the handle 13. 95

21 is a die plate segmental in form and preferably of about 270° extent, that is to say, an opening of about 90° may be left in its front side, for the reason which will be explained herein. The die plate 21 has an 100 overhanging peripheral rim or flange 22 adapted to rest on the shoulder 2 of the base 1. The inner edge of the plate 21 is grooved as at 23. (See Fig. 5.) This groove 23 constitutes the forming recess for 105 clenching the lugs of the cap.

26 is a follower having a circular bearing rim 27 provided with a rib 28 and hav-

ing a central stem 29 which may be pinned as at 30 in the socket 6 in the end of the plunger 5. These followers 26 and dies 21 are provided in different sizes to fit different sized can nozzles and different sized closures.

Referring to Fig. 9 the closure consists of a cap A surrounded by a depending flange or rim B from which engaging fingers depend. These fingers C are usually 4 in number, two smaller ones being arranged close together adjacent to pivot D by the cover E and the other two being arranged at substantially 90° from said point B of pivot D. These fingers C are to be engaged or clenched beneath a shoulder F formed by rolling under the edge of a lip G formed on a neck H. For this reason it is only necessary that the die be slightly greater in circumferential extent than 180°. In my prior patents herein before referred to I have usually shown these shoulder engaging fingers C as curved in order to provide for a spring engagement with a shoulder vessel mouth. Although closures with such curved fingers may be applied to a vessel and subsequently clenched in my machine such prior curving is not absolutely necessary. In fact it is somewhat more convenient to leave these fingers straight so that the closure may be applied direct instead of requiring a lateral movement.

In operating my machine therefore the neck of the filled can is thrust through the open side of the die 21. If a can with a smaller sized mouth is to be sealed, a die having a correspondingly small opening, as indicated at 21¹ Fig. 6 may be used. The closure is then applied with its point of pivot to the rear and its unfingered side toward the open side of the die. This leaves the locking lip F¹ on the open side of the die. At the same time that the closure is placed upon the can a sealing wafer and a pack K are included within the depending flange B. During this operation the plunger 5 is held up by the spring 11 so that the follower 26 is clear of the die. When the can and closure are in place the handle 13 is depressed until the stop 18 permits no further motion. This stop 18 is adjusted so that the follower will advance

just far enough to securely clench the fingers C of the closure without unduly compressing the cover on the closure as will be seen by reference to Figs. 1, 7 and 8. The follower 26 has a recess 27¹ within the circular rim 27. This is to receive the raised center E¹ of the closure E. This center is usually embossed and the recess 27¹ is depended upon to protect this raised center. Upon the release of the handle 13 the spring 11 raises the plunger 5 and the follower 26 and the can neck H may be raised and laterally removed with the closure permanently engaged thereon.

Various modifications may obviously be made in the construction and operation of my device all without departing from the spirit of my invention if within the limits of the appended claims.

What I therefore claim and desire to secure by Letters Patent is:

1. A device for crimping the fingers of a closure beneath the shouldered mouth of a containing vessel, comprising an open sided support, a removable open sided die in said support, said die having a groove about the inner margin thereof, a plunger mounted for vertical reciprocation in said support and a head on said plunger adapted to engage said closure and force said closure and mouth against said die.

2. A device for crimping the fingers of a closure beneath the shouldered mouth of a containing vessel, comprising an open sided support having a supporting shoulder, a removable open sided die having an overhanging margin adapted to bear on the supporting shoulder of said support, said die having a groove about the inner margin thereof, a plunger mounted for vertical reciprocation in said support and a head on said plunger adapted to engage said closure and force said closure and mouth against said die.

In testimony whereof, I affix my signature in presence of two witnesses.

EUGENE D. CHELLIS.
